COMBINED WEATHERSTRIP AND THRESHOLD PLATE OR SIMILAR ARTICLE

Milton J. Smith, Newton Center, Mass.

Application September 17, 1956, Serial No. 42,973

Term of patent 14 years

(Cl. D13—6)

The figure is a perspective view of a combined weatherstrip and threshold plate, or similar article, showing my new design.

The weatherstrip is broken away in the center thereof to indicate indeterminate length.

I claim:

The ornamental design for a combined weatherstrip and threshold plate or similar article, substantially as shown and described.
